(57) **CLAIM**

The ornamental design for a tooth-shaped cake plate, as shown and described.

DESCRIPTION

FIG. 1 is a perspective view of a tapered embodiment of a tooth-shaped cake plate according to the present invention; FIG. 2 is a front view of the tooth-shaped cake plate of FIG. 1;

FIG. 3 is a back view of the tooth-shaped cake plate of FIG. 1; FIG. 4 is a right side view of the tooth-shaped cake plate of FIG. 1;

FIG. 5 is a left side view of the tooth-shaped cake plate of FIG. 1;

FIG. 6 is a top view of the tooth-shaped cake plate of FIG. 1; FIG. 7 is a bottom view of the tooth-shaped cake plate of FIG. 1;

FIG. 8 is a perspective view of a straight-walled embodiment of a tooth-shaped cake plate according to the present invention;

FIG. 9 is a front view of the tooth-shaped cake plate of FIG. 8;

FIG. 10 is a back view of the tooth-shaped cake plate of FIG. 8;

FIG. 11 is a right side view of the tooth-shaped cake plate of FIG. 8;

FIG. 12 is a left side view of the tooth-shaped cake plate of FIG. 8;

FIG. 13 is a top view of the tooth-shaped cake plate of FIG. 8; and,

FIG. 14 is a bottom view of the tooth-shaped cake plate of FIG. 8.
